Application January 3, 1951, Serial No. 13,658

Term of patent 14 years

(Cl. D33—10)

To all whom it may concern:

Be it known that we, Bernard J. Flood and Charles D. Welshenbach, both citizens of the United States and residents of the city of Elkhart, in the county of Elkhart and State of Indiana, and of the city of Sandusky, in the county of Sandusky and the State of Ohio, have jointly invented a new, original, and ornamental Design for a Music Stand or Similar Article, of which the following is a specification, reference being had to the accompanying drawing, forming a part thereof.

In the drawing:

We claim:

The ornamental design for a music stand or similar article, substantially as shown.

BERNARD J. FLOOD.
CHARLES D. WELSHENBACH.
